UNITED STATES PATENT OFFICE.

GUSTAV C. ULLRICH, OF BUFFALO, NEW YORK, ASSIGNOR TO THE REPUBLIC METAL-WARE CO., OF BUFFALO, NEW YORK, A CORPORATION OF NEW YORK.

SPRINKLING CAN.

Application filed July 28, 1926. Serial No. 125,539.

This invention relates to improvements in sprinkling cans or pots.

One of its objects is to provide a receptacle of this character which is designed for spraying shrubbery and the like and which can be readily converted to deliver a solid stream of water for filling automobile radiators or other vessels.

Another object of the invention is the provision of a simple and inexpensive combination sprinkling can whose spout is so constructed as to readily enter the filling neck of an automobile radiator or the like without danger of its displacement while emptying the contents of the can.

In the accompanying drawings: Figure 1 is a side elevation of a sprinkling can embodying my invention, the sprinkler-head being removed and the can being shown in position for filling an automobile radiator. Figure 2 is a similar view, partly in section, with the sprinkler-head applied to the spout.

Similar characters of reference indicate corresponding parts in both figures.

The sprinkling can is preferably constructed of sheet metal and consists of a cylindrical body 10 of any appropriate dimensions having a suitable handle 11 extending around from the rear side of said body to the upper end of the opposite side. Projecting upwardly and outwardly from the lower front side of the can-body is a conical-shaped spout 12 through which the water is discharged when the can is tilted forwardly. The discharge end of this spout terminates in an annular flange 13 and permanently joined thereto is the attaching-base 14 of a discharge nozzle 15 intended to deliver a solid stream of water. The lower portion or shank of the discharge-nozzle is externally threaded to receive a detachable rose or sprinkler-head 16 whose hollow base is bowl-shaped, as shown, and has the usual removable perforated cap 17 applied thereto for delivering the water in a fine spray, as when sprinkling shrubs, flowers, etc.

As shown in Fig. 2, the nozzle 15 extends into the hollow base of the sprinkler-head 16 and is curved outwardly into approximately hook-shape. By this construction, the discharge nozzle can be readily inserted into the filling neck 18 of an automobile-radiator or other vessel and the contents of the can poured into the same at a convenient angle to

the user, it being only necessary to bring the can into a substantially horizontal position to effect the complete discharge of its contents. Furthermore, by shaping the nozzle in this manner, its outlet end extends downwardly into the filling neck of the radiator, preventing splashing of the water over the hood of the car. The hook-shaped nozzle, when engaged with the radiator filling neck, is effectually prevented from slipping out of position and it forms a reliable fulcrum or bearing for the can during the tilting movement thereof to discharge its contents.

This improved sprinkling-can is very useful around private and public garages, and it can be readily converted for use to deliver either a spray for sprinkling purposes or a solid stream for filling radiators and the like, thereby eliminating the necessity of separate receptacles for such work and accordingly affording a saving to the user.

I claim as my invention:

1. A sprinkling can, comprising a cylindrical body having a spout extending therefrom, a nozzle applied to the discharge end of the spout for delivering a solid stream of fluid, the shank of said nozzle having an external screw thread thereon and the portion thereof forwardly of the screw thread being curved outwardly, and a perforated sprinkler-head detachably connected to the threaded-shank of the nozzle, the curve portion of the latter extending into said sprinkler-head with its outlet end discharging laterally into the head below the perforations thereof.

2. A sprinkling can, comprising a cylindrical body having a spout extending therefrom, the discharge end of the spout terminating in an attaching flange, a nozzle applied to said spout and joined to its attaching flange, the shank of said nozzle having an external screw thread thereon and the remaining portion thereof forwardly of the screw thread being substantially hook-shaped and forming a fulcrum for the can in tilting it to discharge its contents, and a perforated sprinkler-head detachably connected to the threaded-shank of the nozzle, the hook-shaped portion of the latter extending into said sprinkler-head and at the lower side thereof, below the perforations of the head.

GUSTAV C. ULLRICH.
